VARIABLE-VOLTAGE-CONTROL SYSTEM

Application filed February 6, 1922. Serial No. 584,404.

Our invention relates to motor-control systems and it has particular relation to such systems of control as are employed in connection with elevators, hoists and similar machines.

One object of our invention is to provide means for controlling the effect of the field excitation of a generator that is employed for supplying energy to a hoist motor.

10 Another object of our invention is to provide a system of elevator control that is automatic in its operation, within certain limits, for effecting accurate stops of the elevator car independently of the skill of the car operator.

We propose to employ a system embodying what is known as the Ward Leonard connection. For controlling the stopping or retardation of the hoist motor, we employ a relay having its operating coil connected in series relation with the separately excited field-magnet winding of the generator. A suitable circuit is established by the relay contact members when the field winding is 25 normally energized. Switches are provided for reversing the generator field winding and have back-contact members for completing a discharge path in shunt relation to the generator field-magnet winding.

25 When the reversing switches are opened to deenergize the field-magnet winding, a discharge circuit is maintained through the operating coil of the above-mentioned relay, until the field current has reached a predetermined low value, whereupon the relay interrupts the field discharge circuit. A circuit is then established through back-contact members of the relay, whereby the separately excited field-magnet winding of the generator

40 is connected across the generator-armature terminals in such relation as to de-energize the generator field-winding. The foregoing method of controlling the generator-field magnetization prevents too rapid deceleration of the hoist motor.

The elevator car is normally controlled by a car switch in a well-known manner. In addition, a rheostat is provided in the car for controlling the field excitation of the generator. For insuring accurate stopping of

the car, we prefer to employ a switch on the car that is actuated by cams, suitably arranged in the hatchway, which operate to bring the car substantially to a level with the desired floor.

55 Figure 1 of the accompanying drawing is a diagrammatic representation of circuits and apparatus embodying our invention.

Fig. 2 is a simplified diagrammatic view of the main circuits illustrated in Fig. 1.

60 Referring particularly to Fig. 1, a hoist motor having an armature 1 is connected in a "loop" circuit that receives energy from a generator having an armature 2 and a series field-magnet winding 3. Any suitable means 65 may be provided for driving the generator armature. The separately excited field-magnet windings 4 and 5 of the motor and generator, respectively, are supplied with energy from any suitable source, represented 70 as a battery 6. Mechanically interlocked reversing switches 7 and 8 control the connections of the generator separately excited field-magnet winding.

75 A relay 9 is provided with an operating coil 10 for connection in circuit with the separately excited field-magnet winding 5 of the generator. During normal operation of the generator, the relay coil 10 is energized to interrupt a circuit through a back-contact 80 member 11 of the relay 9. Therefore, upon opening the circuit of the separately excited field-magnet winding 5 by means of reversing switch 7 or reversing switch 8, a local circuit is established, comprising the field-magnet 85 winding 5, relay coil 10 and an adjustable resistor 12 of low ohmic value.

90 At a predetermined value of the generator field current, relay 9 opens the circuit through resistor 12 and closes a circuit through the contact members 7^c and 8^c of reversing switches 7 and 8 to connect the field-magnet winding 5 in shunt relation to the generator armature 2. In this manner, the generator field current is first controlled in accordance 95 with the value of resistor 12 and then is entirely dissipated by connecting the field-magnet winding in proper relation to the generator armature, which is then supplying a voltage opposed to that of the field-magnet 100

winding 5. The effect of this connection of the separately excited field winding of the generator is to completely demagnetize the generator field, overcoming the normal residual magnetism of the field iron and the magnetizing effect of the series field winding. The voltage of the generator is thus reduced to zero and the motor is stopped. Obviously, the inherent characteristics of such connection 5 are such as to effect a dynamic-braking action the force of which is proportional to the current in the motor armature circuit and, hence, proportional to the load on the motor. Deceleration of the armature 1 is smoothly 10 effected and any tendency towards creepage 15 of the elevator is eliminated upon complete demagnetization of the generator field winding.

An electromagnetic brake 13 is controlled 20 by a relay 14, in a well-known manner, for assisting in stopping the armature 1 and for maintaining it in its inoperative position. An elevator car 15, which is adapted to be driven by the armature 1, is controlled by a car 25 switch 16 and a generator-field-rheostat 17; the latter may be independently operated or may be operatively connected to the car switch. In the "Off" position of the car switch 16, a slow operating speed of the hoist 30 motor may be obtained by means of an auxiliary switching mechanism having "up" and "down" reversing switches 18 and 19, respectively.

A cam 21 is located adjacent to the path of 35 the car at each floor and co-operates with contact members 18 and 19. Various safety devices which are not essential to the operation of our system have been omitted from the drawing. We have, however, provided 40 overtravel limit switches 22 and 23 and an overspeed governor switch 24 that is controlled in accordance with the speed of the motor armature 1.

Referring particularly to Fig. 1 of the 45 drawing, we may assume the elevator car 15 to be at the second floor, the control switches in their inoperative, or illustrated, positions, and the armature 2 of the generator operating at normal speed with no field excitation.

To operate the car to the third floor, the car switch 16 is actuated to the right from its illustrated position, thereby establishing a 50 circuit for the operating coils of the reversing switch 7 and of the brake relay 14 extending from the positive terminal of battery 6, through overspeed governor switch 24, limit switches 22 and 23, operating coil of relay 14, operating coil of reversing switch 7, and car switch contact members 25 and 26, to the 55 negative terminal of the battery 6.

Reversing switch 7 and relay 14 thereupon 60 close to complete circuits for the generator shunt field-magnet winding 5 and the operating coil of electromagnetic brake 13, respectively, the latter having its operating coil

directly connected, through the relay 14, to the battery 6. A circuit for the field-magnet winding 5 extends from the positive terminal of the battery 6, through conductor 27, contact member 7^a of reversing switch 7, field-magnet winding 5, relay coil 10, contact member 7^b of reversing switch 7 and rheostat 17, to the negative terminal of the battery 6. 70

The consequent release of electromagnetic brake 13 permits the hoisting motor to operate at a slow speed, which is determined by the field excitation of the generator. The field rheostat 17 is next operated to reduce the amount of resistance in the generator field-winding circuit and to effect a corresponding 75 increase in the voltage generated and delivered by the generator armature to the armature 1 of the hoisting motor. 80

The energization of the field-magnet winding 5 effects the closure of relay 9 by means 85 of operating coil 10, the energizing circuit for which has already been traced. The function of relay 9 is to control circuits that are established during slow-down of the hoisting motor, as will be described later. 90

It will be noted that the series field winding 3 for the generator 2 will be excited in proportion to the load upon the elevator motor 1 and will effect an increase or decrease in the total field strength of the generator 2 to 95 correspond to the variations in load upon the elevator car 15. That is, with a heavy lifting load, the field strength of the generator 2 will be built up correspondingly, and, with a descending overhauling load, the field 100 strength will be weakened correspondingly, thereby producing a regulating effect upon the motor 1 to maintain the speed of the motor substantially uniform under various loading conditions. 105

As the elevator car 15 approaches the third floor, the car switch 16 is returned to its inoperative or "Off" position to effect a landing. In case the car 15 tends to stop before attaining the level of the third floor, switch member 18 is actuated by the cam 21 to maintain a slow operating speed of the hoisting motor by establishing contact between the stationary contact member 28 and the movable switch member 18, which are electrically connected to contact members 26 and 25, respectively. The operating circuit previously traced is, therefore, maintained until the car attains the desired level. 110

It is assumed that, prior to the release of 120 car switch 16 by the operator, the desired slow operating speed is effected by manipulation of the rheostat 17, so that there is sufficient energy supplied from the generator to the motor armature 1 to insure response to the actuation of the leveling-switch member 18. When the car 15 is substantially level with the third floor, switch members 18 and 19 assume positions corresponding to that 125 illustrated, with respect to the cam 21, and 130

the circuit for reversing switch 7 and brake relay 14 is interrupted by the separation of switch member 18 from stationary contact member 28.

Upon opening, reversing switch 7 establishes a circuit, through its back contact member 7^c, that provides a discharge path for the current in the separately excited field winding 5. The time required to discharge the field-magnet winding 5 is determined by the effective value of the resistor 12, which is now connected in a circuit extending from one terminal of field-magnet winding 5 through back contact-member 8^c of reversing switch 8, resistor 12, relay 9, back-contact member 7^c of reversing switch 7, and coil 10 of relay 9 to the other terminal of field-magnet winding 5.

When the current in the generator separately excited field winding has fallen to a suitable value, relay 9 opens and establishes a circuit through its back-contact member 11 to connect the field-magnet winding 5 across the terminals of the generator armature 2. The connections are predetermined in such manner as to insure complete de-energization of the field-magnet winding 5, as previously explained.

It may be assumed that current originally traversed the armature 2 in the direction indicated by the corresponding arrow, prior to stopping the car at the third floor. It may also be assumed that the current traversing field-magnet winding 5 flowed in the direction indicated by the corresponding arrow. It will be noted that the current in the winding 5 flows in the opposite direction to the current traversing the armature 2, when the armature and field-magnet windings are connected through the back-contact member 11 of relay 9.

The circuit through field-magnet winding 5 at this time extends, through the relay coil 10, back-contact member 7^c, relay contact-member 11, armature 2, and back-contact member 8^c to field-magnet winding 5.

If, however, the flow of field current is in the opposite direction to that first assumed, the main current through generator armature 2 also flows in the opposite direction, and, since the relative directions of currents are, in this case, the same, the resultant effect is unchanged, whereby complete discharge of the generator field-magnet winding 5 is insured, irrespective of the direction of the operating current traversing the armatures 1 and 2. The direction of this operating current, of course, is normally determined by the direction of the current through the generator field-magnet winding 5 and is controlled by reversing switches 7 and 8 and in a well-known manner.

The value of the current supplied to the separately excited field winding 5 of the generator 2 under these conditions will obviously

be in proportion to the load on the motor during its period of deceleration.

The necessity for a complete demagnetization of the generator field-magnet winding is evident, since the operation of the motor armature 1 is controlled thereby. Under certain load conditions of the elevator, a slight field excitation is sufficient to cause the armature 1 to rotate at a very slow or creeping speed in spite of the setting of the brake 13. This action is detrimental to the control of the elevator, since it is desirable to effect accurate stopping independently of the load in the elevator car.

It will also be understood that, in passenger elevator service particularly, it is not desirable, in stopping, to immediately connect the shunt field-magnet winding 5 in the previously described reversed relation to the armature 2, before slowing down the elevator, because reduction in the speed of armature 1 is thereby effected too abruptly. We have, therefore, provided a relay 9 which is controlled by the excitation of the field-magnet winding 5 in such manner as to insure a predetermined degree of slow down of the hoisting motor prior to establishing these reversed field-winding connections.

In case the elevator operator failed to release the car switch 16 soon enough, the car 95 would travel beyond the level of the third floor. In such case, cam 21 would actuate switch member 19 to engage stationary contact member 28, thereby completing a circuit for the reverse direction of operation of the 100 armature 1 by effecting the closure of reversing switch 8 and brake relay 14 and the consequent release of the electromagnetic brake 13. The circuit for the operating coils of relay 14 and switch 8 extends from one 105 terminal of battery 6, as previously traced, through governor switch 24, limit switches 22 and 23, the operating coils of relay 14 and switch 8, and contact members 19 and 28, to the other terminal of battery 6. The 110 control system for effecting movement of the car downward, within the leveling zone, which movement is controlled by the cam 21, is similar to that described for the upward motion.

Operation of the elevator downward, by the movement of the master switch to the left of its illustrated position, is effected in a manner similar to the upward movement and is so well understood by those familiar with elevator operation that it is considered unnecessary to further explain the details of operation.

In practice it will be found advantageous to control the rheostat 17 in accordance with 125 the movement of the car switch 16, so that minimum field excitation is provided prior to returning the car switch to its inoperative position.

Our system of control is simple and effec- 130

- tive and the automatic control of the field excitation, during deceleration of the elevator, has been found to be of great value in connection with a Ward Leonard system. Other 5 means for controlling the relay 9 are at once apparent, as for example, to connect the operating coil 10 across the terminals of the armature, or to otherwise control it in accordance with the speed of the hoisting motor. 10 If desired, the relay 9 may be controlled by a time-limiting device of any well known character, such as a dash pot.

Modifications of our system will be apparent to those familiar with the art and may 15 be made without departing from the spirit of our invention. Therefore, we do not wish to be limited to the exact methods that we have found preferable.

We claim as our invention:

20 1. The combination with a generator and a motor electrically connected thereto, of means for controlling the degree of excitation of a field-magnet winding of said generator, and a switch controlled in accordance with the 25 value of the field current for further controlling the excitation of said winding.

2. The combination with a motor and a generator for supplying energy to the motor, of a source of energy for a field-magnet winding 30 of said generator, a discharge circuit, effective upon failure of said energy, for controlling the rate of change in the field current, and a relay controlled in accordance with the 35 value of said field current for controlling said discharge circuit.

3. The combination with a motor and a generator for supplying energy to the motor, of electro-responsive means for connecting a field-magnet winding of said generator in a 40 closed circuit of low resistance and for thereafter automatically connecting the armature and the field-magnet winding in a closed circuit, to effect a gradual reduction in speed of said motor.

45 4. The combination with a generator having a shunt type field-magnet winding, of a source of energy, means for connecting the field-magnet winding to the source of energy, means for short-circuiting said winding when 50 said winding is disconnected from said source, and means responsive to current traversing said winding for connecting said winding in circuit with the generator armature to dissipate energy from said winding.

55 5. The combination with a generator having a field magnet and a shunt type field-magnet winding thereon and means, comprising reversing switches and a relay controlled in accordance with the value of the current 60 traversing said winding, for connecting said winding in shunt relation to the generator armature to effect de-energization of said field magnet.

6. The combination with an elevator car 65 and a hoisting motor therefor, of a generator

for controlling the motor, a reversing switch for controlling the effect of a field-magnet winding of said generator, a switch controlled by the movement of the car for controlling the reversing switch, and a relay controlled in accordance with the value of the generator field-current for further controlling the generator. 70

7. The combination with an elevator car and a hoisting motor therefor, of a generator for controlling the motor, means controlled in accordance with the movement of the car for controlling the field excitation of the generator, and means controlled in accordance with the value of the generator field-current 75 for further controlling said generator.

8. The combination with an elevator car and a hoisting motor therefor, of a generator for controlling the motor, a switch controlled in accordance with the movement of the car 80 for controlling the effect of a field-magnet winding of said generator, and a switch controlled in accordance with the value of the current traversing said winding for further controlling the generator.

9. The combination with an elevator car and a hoisting motor therefor, of a generator having a shunt type field-magnet winding for controlling the motor, reversing switches for the field-magnet winding controlled in accordance with movements of the car, and a relay co-operating with the reversing switches and controlled in accordance with the value of the current traversing said field-magnet winding, for controlling said generator. 90

10. The combination with an elevator car and a hoisting motor therefor, of a generator having a shunt type field-magnet winding for controlling the motor, reversing switches for the field-magnet winding controlled in accordance with movements of the car, and a relay, co-operating with the reversing switches and controlled in accordance with the value of the current traversing said field-magnet winding, for controlling the effect of said field-magnet winding. 100

11. The combination with an elevator car and a motor therefor, of a generator having a shunt type field-magnet winding and electrically connected to the motor, reversing switches for controlling the shunt-field-magnet winding, a switch controlled by movements of the car for controlling the reversing switches, and a relay co-operating with said reversing switches and controlled in accordance with the value of the current traversing said field-magnet winding for modifying the effect of said reversing switches. 115

12. The method of decelerating a motor connected in circuit with a generator which consists in interrupting the generator field-winding circuit, establishing a discharge 120

circuit for the field-magnet winding to control the rate of decay of the field magnetization and finally interrupting the discharge circuit at a predetermined value of field current and connecting the field-magnet winding in circuit with the generator armature to entirely dissipate the energy of said generator field.

10 In testimony whereof, we have hereunto subscribed our names this 10th day of January, 1922, and this 19th day of January, 1922, respectively.
